SHEET FEEDING APPARATUS

Edward R. Kast, Pearl River, N. Y., assignor to
 Dexter Folder Company, Pearl River, N. Y., a
 corporation of New York

Application August 11, 1938, Serial No. 224,237

4 Claims. (Cl. 271—46)

This invention relates to sheet feeders for feeding sheets to printing presses or other machines and while capable of general use is more particularly adapted for feeding sheets in lapped relation to the grippers or other sheet taking devices of the printing press or other instrumentality with which the feeder is associated.

One object of the present invention is to provide a sheet feeder for advancing a stream of lapped sheets to a printing press or other instrumentality and having novel means for maintaining a definite amount of lap between each sheet of the stream.

Another object of the present invention is to provide a sheet feeder for advancing a stream of lapped sheets to a printing press or other instrumentality and having novel means for preventing sliding movement of the sheets relative to each other and thereby insuring delivery of each sheet at the proper time to the front stops or registering devices of the printing press.

Another object of the present invention is to provide a sheet feeder for advancing a stream of lapped sheets to a printing press or other instrumentality and having improved means for straightening each sheet of the stream before delivery thereof to the front stops or registering devices of the printing press.

These and other objects of the present invention will appear as the following description thereof proceeds, and in order to more clearly understand said invention reference may be had to the accompanying drawings which illustrate one embodiment thereof.

In said drawings:

Fig. 1 is a side elevation, partly in section, of a sheet feeder embodying the present invention;

Fig. 2 is a top plan view of said feeder with parts omitted for purposes of clearer illustration;

Fig. 3 is an enlarged side elevation of a sheet engaging hook and mounting therefor shown in Figs. 1 and 2;

Fig. 4 is an enlarged top plan view of the sheet engaging hook shown in Fig. 3;

Fig. 5 is an enlarged end view of the sheet engaging hook looking from the right of Figs. 3 and 4; and

Fig. 6 is a side elevation showing diagrammatically the manner in which the sheets are separated and forwarded in lapped relation from a pile, and the action of the sheet engaging hooks on a stream of lapped sheets.

Referring to the drawings, wherein like reference characters designate like parts throughout

the several views, 5 indicates part of the frame of a feeder which is supported by upright posts or standards 6 and includes a pile elevator comprising a pile board 7 adapted to support a pile of sheets 8. The pile board 7 and pile of sheets 8 thereon are raised intermittently in the usual manner, to keep the top of said pile at a predetermined level, by chains 9 the links of which engage in the teeth of sheaves 10 that are fixed on shafts 11 journaled in suitable bearings on feeder frame 5. The shafts 11 are driven from any suitable source of power by gearing connected therewith and including worm wheels 12 fixed on shafts 11.

The sheets of pile 8 are separated one after another from the top of the pile by suction separating devices 13, indicated diagrammatically in Fig. 6 of the drawings, which are adapted to engage opposite rear corners of each successive sheet and lift the rear edge thereof above the level of the pile. Prior to release of the separated and lifted sheets by the suction separating devices 13, said sheets are engaged at the rear thereof by suction forward devices 14 (Fig. 6) which forward the sheets, when released by the suction separating devices 13, a short distance from the pile in lapped relation one under another, as illustrated in Fig. 6 to conveying means that are continuously driven at slow speed to enable lapping of the sheets thereon. This conveying means advances the lapped sheets to a printing press or other instrumentality with which the feeder is associated, and as herein shown, is preferably constructed and operated as follows.

Extending transversely of the feeder and journaled in suitable bearings in the feeder frame 5 is a feed roller 15 around which passes a series of conveyor tapes 16 that also pass around a transversely extending roller 17 journaled in suitable bearings in front end frames 18. The upper reaches of the tapes 16 pass over a roller 19 journaled in suitable bearings in the feeder frame 5, also over a forwardly and downwardly extending feed board 20 which is suitably supported at opposite ends thereof on the feeder frame 5 and front end frames 18, respectively. The lower reaches of tapes 16 pass under suitable tape tightening rollers 21 carried by the feeder frame 5. Cooperating with the feed roller 15 are pressure rollers 22 journaled on arms 23 which are adjustably secured on a shaft 24 that extends transversely of the feeder and is fixed in the feeder frame 5.

The slow speed drive for the feed roller 15

and tapes 16 is preferably effected from a single revolution or cam shaft 25 which extends transversely of the feeder and is journalled in suitable bearings in the feeder frame 5. This cam shaft 25 is connected in any suitable manner with, and driven by, the printing press or other machine to be fed, and is also utilized, through the medium of suitable mechanism (not shown), to impart motion to the sheet separating and forwarding devices 13, 14 respectively for separating and forwarding the sheets one after another in lapped relation between the feed and pressure rollers 15, 22, respectively. Fixed on the cam shaft 25 is a spur gear 26 which meshes with a similar gear 27 that is journalled on a stud 28 fixed in any suitable manner on the feeder frame 5. Secured to or formed integrally with the spur gear 27 is a similar gear 29 which meshes with a spur pinion 30 that is journalled in any suitable manner on the feeder frame 5. The spur pinion 30 meshes with a similar pinion 31 that is fixed on the feed roller 15 and which through the described driving connections therefor with the cam shaft 25 drives the feed roller 15 25 and conveyor tapes 16 at a slow speed to enable lapping of the sheets thereon.

The front end frames 18 support front end mechanism including front and side registering devices hereinafter referred to. These front end frames 18 are bolted or otherwise suitably secured to the frames 32 of the printing press or other machine to which the sheets are fed. Frames 18 are also connected with the frame 5 of the sheet feeder as by tie bars 33 which are bolted or otherwise suitably secured to the feeder frame 5 and front end frames 18 respectively. The front end frames 18 are connected together by stay shafts 34, 35, 36 and 37.

In accordance with the present invention the sheet feeder is provided with means for straightening each sheet of the stream of sheets during movement thereof on the conveyor; for preventing sliding movement of the sheets on the conveyor relative to each other; for maintaining a definite predetermined amount of lap between the sheets of the stream on the conveyor; and for thereby insuring delivery of each sheet at the proper time and in proper straightened condition to the front stops or registering devices of the printing press or other machine with which the feeder is associated. Said means are preferably mounted, constructed and operated as follows.

Bolted or otherwise suitably secured to the tie bars 33 are brackets 38 which, in turn, have adjustably secured thereto, as by bolts 39, brackets 40. Extending transversely of the conveyor beneath the feed board 20 and the upper reaches of tapes 16 is a shaft 41 which is journalled in suitable bearings in the brackets 40. Fixed on and spaced along shaft 41 are two sprockets 42 around which pass chains 43 that also pass around sprockets 44 at the forward end of the conveyor. Sprockets 44 are journalled on pins 45 secured in any suitable manner in arms 46 which are secured to the stay shafts 36 and 37. The upper reaches of the chains 43 pass through longitudinally extending slots or openings 47 in the feed board 20 and grooves 48 formed in the tape roller 17, and are guided on track bars 49 which are suitably supported at opposite ends thereof on the feed board 20 and stay shaft 36, respectively.

Each chain 43 is provided at intervals therealong with a plurality of sheet engaging hooks indicated broadly at 50 and spaced apart so that the distance between the hooks is equal to the

distance between the front edge of a preceding sheet and the front edge of a succeeding sheet lapped therewith. As shown in Figs. 3, 4 and 5 of the drawings these sheet engaging hooks 50 consist of U-shaped members 51 which engage over the chains 43 and are connected therewith by pins 52 that pass through said members and corresponding links of said chains. Endwise displacement of pins 52 is prevented by cotter pins 53 inserted in opposite ends thereof. Pivotally connected with one of the pins 52 of members 51 are other U-shaped members 54 which also engage over the chains 43 and are connected therewith by pins 55 that pass through said members and other corresponding links of said chains. Endwise displacement of pins 55 is prevented by cotter pins 56 inserted in opposite ends thereof. Each of the U-shaped members 55 is provided with a sheet engaging abutment 57 which extends slightly above the tapes 16 through the slots 47 in feed board 20, and a cover portion 58 for guiding the front edge of the sheet into engagement therewith.

The chains 43 and sheet engaging hooks 50 thereon are continuously driven at a surface speed slightly slower than the surface speed of the tapes 16 so that the sheets will be advanced into engagement with said hooks by the faster moving tapes 16 which will then slip relative to said sheets and hold the latter in contact with the hooks throughout the forward movement of said tapes and chains. This slower speed drive for the chains 43 is, like the slow speed drive for the tapes 16, effected in the following manner from the single revolution or cam shaft 25 so that for each revolution of said shaft and for each sheet forwarded from the pile in lapped relation with a preceding sheet a pair of transversely aligned sheet engaging hooks 50 will be in proper position to receive the sheets.

Secured to or formed integrally with the spur gear 26 is a similar gear 59 which meshes with a spur gear 60 that is journalled on the shaft 24. Secured to or formed integrally with the spur gear 60 is a sprocket 61 around which passes a chain 62 that also passes around a sprocket 63 that is fixed on the shaft 41. The upper reach of the chain 62 passes under a suitable chain tightening sprocket 64 journalled on an arm 65 that is adjustably secured on a bearing pin 66 for one end of the tape roller 19. It will thus appear that due to the difference in surface speed between the tapes 16 and chains 43 each succeeding lapped sheet after the rear edge thereof passes from between the feed and pressure rollers 15 and 22, respectively, will be advanced by the faster moving tapes 16 a short distance relative to a preceding lapped and hooked sheet, until the forward edge of the sheet engages the following pair of transversely aligned hooks 50 and is straightened thereagainst. At this time the tapes 16 will slip relative to the sheet and hold the latter in engagement with the hooks 50 during forward movement thereof imparted thereto by said tapes and until it is released by said hooks which occurs at the time the hooks pass around the sprockets 44 and away from said sheet. It will further appear that engagement of the lapped sheets with the hooks 50 which, as previously described are spaced a predetermined distance apart, establishes and maintains a definite amount of underlap between each sheet of the stream as indicated diagrammatically in Fig. 6 of the drawings, and also prevents sliding movement of the sheets relative to each other thereby insuring delivery of each sheet at the

proper time to front stops or registering devices 67 of the printing press or other machine with which the feeder is associated.

After the leading sheet of the stream is released 5 by the hooks 50, said sheet is advanced a short distance by the moving stream of lapped sheets into engagement with the front stops or registering devices 67 to be front registered.

Movement of the leading sheet the short distance into engagement with the front stop or registering device 67, as well as the movement of the remaining sheets of the stream along the conveyor is insured by a plurality of spring pressed 10 rider wheels 68 which are spaced along a plurality of top rods 69 extending longitudinally of the feed board 20 above the driven tapes 16 and serving to prevent displacement of the sheets therefrom. These top rods 69 are adjustably secured in brackets 70 which are clamped, as by thumb 15 screws 71, to the stay shaft 34. The rider wheels 68 at the front end of the conveyor hold the leading sheet against displacement when released by the hooks 50 until the forward edge thereof engages the front stops or registering devices 67.

25 The front stops or registering devices 67 are carried on arms 72 which are secured in any suitable manner on a rock shaft 73 extending transversely of the front end mechanism and journaled in suitable bearings in the front end frames 18. 10 The shaft 73 is oscillated from the press or other machine by suitable means (not shown) to move the front stops or registering devices 67 into and out of the path of the sheet at proper intervals. The front portions of the sheets during their 15 movement from the tapes 16 to the front stops or registering devices 67 are supported by spaced tongues 14 which are secured in any suitable manner on the stay shaft 36.

After the forward edge of the sheet has been 10 accurately positioned against the front stops or registering devices 67, said sheet is moved laterally to side register the same with respect to the press or other machine by a side registering device indicated broadly at 75. The mounting, 15 construction and operation of the side registering device is preferably the same as the mounting, construction and operation of the side registering devices disclosed in the application of Edwin W. Goodwin, Serial No. 62,706, filed February 6, 1936 and needs no detail description herein. 20 After the sheet has been side registered, the front stops or registering devices 67 are moved downwardly out of the path of the sheet and said sheet is engaged at the forward end thereof by transfer grippers 76 or other devices and drawn from the conveyor into the printing press or other machine to be further acted upon.

The operation of a feeder constructed in accordance with the present invention will be clearly understood from the foregoing description and while said description and the accompanying drawings set forth with more or less particularity one embodiment of the invention, it is to be expressly understood that said invention is not limited to said embodiment or otherwise than by the terms of the appended claims.

What I claim is:

1. In a sheet feeding apparatus, a conveyor including a plurality of tapes for advancing a 0 stream of lapped sheets toward a machine to be fed, means for driving said tapes at a slow speed, a plurality of transversely spaced chains extending along the tapes and having series of sheet engaging members spaced a predetermined distance apart, said chains and said tapes being

arranged in the same plane beneath the stream of lapped sheets and said sheet engaging members projecting upwardly from the chains and traveling therewith in the same direction as the tapes, and means for driving said chains and 5 sheet engaging members at a speed slower than the speed of the tapes whereby each sheet of the stream while being advanced by the tapes is moved thereby into engagement with said members and held thereagainst during forward movement of said sheets imparted thereto by said tapes. 10

2. In a sheet feeding apparatus, a feed board, a plurality of tapes for advancing a stream of lapped sheets over the feed board, means for driving said tapes at a slow speed, a plurality of chains extending along the tapes and arranged beneath the feed board, a plurality of sheet engaging hooks carried by the chains at corresponding positions thereon and spaced equal distances apart along the chains, and means for driving said chains at a speed slower than the speed of the tapes whereby each sheet of the stream is moved by the tapes into engagement with corresponding hooks on the chains and 20 held against said hooks while being advanced by said tapes. 25

3. In a sheet feeding apparatus for feeding sheets in lapped relation to a printing press, the combination with a continuously driven slow 30 moving endless conveyor for advancing a stream of the lapped sheets toward the front registering devices of the printing press, of means for establishing and maintaining a definite amount of lap between adjacent sheets of the moving 35 stream and for insuring presentation of the leading sheet of the stream to said front registering devices with said definite amount of overlap maintained relative to the succeeding sheet, said last named means comprising continuously driven 40 slower moving endless means extending along the conveyor toward the front registering devices and in the same plane with the conveyor, and sheet engaging elements carried by said endless means and spaced therealong equal distances 45 apart, said conveyor acting to impart relative movement to the lapped sheets and to engage the leading edges of successive lapped sheets with successive elements of said slower moving endless means. 50

4. In a sheet feeding apparatus for feeding sheets in lapped relation to a printing press, the combination with a continuously driven slow moving endless conveyor for advancing a stream of the lapped sheets toward the front 55 registering devices of the printing press, of means for straining each sheet of the moving stream, for preventing sliding movement of the straightened sheets relative to each other during movement imparted thereto by the conveyor, and for insuring delivery of each sheet at the proper time 60 to said front registering devices and in straightened condition, said last named means comprising continuously driven slower moving endless means extending along the conveyor toward the 65 front registering devices and in the same plane with the conveyor, and pairs of laterally spaced sheet engaging elements carried by said endless means and spaced therealong equal distances apart, said conveyor acting to impart relative 70 movement to the lapped sheets and to engage and hold the leading edges of successive lapped sheets in contact with successive pairs of elements of said slower moving endless means. 75

CERTIFICATE OF CORRECTION.

Patent No. 2,201,539.

May 21, 1940.

EDWARD R. EAST.

It is hereby certified that error appears in the printed specification of the above numbered patent requiring correction as follows: Page 3, second column, line 57, claim 4, for the word "straining" read --straightening--; and that the said Letters Patent should be read with this correction therein that the same may conform to the record of the case in the Patent Office.

Signed and sealed this 12th day of November, A. D. 1940.
